(Cl. D81—1)

To all whom it may concern:

Be it known that we, Perry N. Hobbs and Cullie C. Merchant, citizens of the United States, and respectively residing at Brimson, Grundy County, Missouri, and Ridgeway, Harrison County, Missouri, have invented a new, original, and ornamental Design for Heat Circulating Units, of which the following is a specification, reference being had to the accompanying drawing, forming part thereof.

In the said drawing—

Figure 1 is a front elevation of a heat circulating unit, showing our new design.

Figure 2 is a top plan view of the same.

Figure 3 is a side elevation of the same.

We claim:

The ornamental design for a heat circulating unit, as shown.
